TELEPHONE HANDSET HANGER

Ned T. Stilgenbauer, 1690 Summit Hills Drive,
Cincinnati, Ohio 45230

Filed June 27, 1974, Ser. No. 483,680

Term of patent 14 years

Int. Cl. D14—03

U.S. Cl. D26—14 A

FIG. 1

FIG. 2

FIG. 3

FIG. 4

FIG. 5

FIG. 1 is a front perspective view of a telephone handset hanger showing my new design;

FIG. 2 is a side elevation thereof;

FIG. 3 is a front elevation thereof;

FIG. 4 is a top plan view thereof; and

FIG. 5 is a bottom plan view thereof.

I claim:

The ornamental design for a telephone handset hanger, substantially as shown and described.
